(57) **CLAIM**

The ornamental design for a display apparatus for products and product images, as shown and described.

DESCRIPTION

FIG. 1 is a perspective view of a display apparatus for products and product images.

FIG. 2 is a front elevation view of the display apparatus of FIG. 1.

FIG. 3 is a top plan view of the display apparatus of FIG. 1.

FIG. 4 is a bottom plan view of the display apparatus of FIG. 1.

FIG. 5 is a left elevation view of the display apparatus of FIG. 1.

FIG. 6 is a rear elevation view of the display apparatus of FIG. 1.

FIG. 7 is a right elevation view of the display apparatus of FIG. 1.

FIG. 8 is a perspective view of a display apparatus of FIG. 1 with additional environmental objects shown in broken lines.

FIG. 9 is a front elevation view of the display apparatus of FIG. 8.

FIG. 10 is a top plan view of the display apparatus of FIG. 8.

FIG. 11 is a bottom plan view of the display apparatus of FIG. 8.

FIG. 12 is a left elevation view of the display apparatus of FIG. 8.

FIG. 13 is a rear elevation view of the display apparatus of FIG. 8; and,

FIG. 14 is a right elevation view of the display apparatus of FIG. 8.

The broken lines are included for illustrative purposes only and form no part of the claimed design.
